UNITED STATES PATENT OFFICE

2,599,925

VENTILATING SYSTEM

Edward Lamb, San Francisco, Calif.

Application January 19, 1946, Serial No. 642,317

1 Claim. (Cl. 114—211)

1

This invention relates generally to a ventilating system, and more specifically, to such system in a ship.

In ships, ventilation is generally either natural or artificial, i.e., without the aid of fans or with fans. Of course, where there are ample ports and hatches the same condition exists as in a house, and no other provision for ventilation is required although where high temperatures are encountered, artificial ventilation is desirable. In those instances which are quite common, where a ship's hold has been fumigated, the present ventilating systems whether of the plenum or exhaust type, are very inadequate for removing the gas, and a ship may be tied up for many valuable hours waiting for the gas to be cleared out sufficiently to enable loading of cargo, or the removal of cargo where the fumigation process has been practiced before the cargo has been unloaded.

One of the objects of this invention is the provision of a system or of means whereby the hold of a ship may be cleared of gas far more quickly than heretofore, and which means is free from the hazards of sparks from fan motors.

Where fire occurs in the hold of a vessel the present methods for attempting to subdue the same involves flooding the particular hold or compartment with water or attempting to smother it with gas or foam. Also in some instances, the hold in which the fire has broken out may be closed off in the hope that the fire will find insufficient oxygen to support it. This latter condition is rarely attempted and is more rarely successful.

Another object of this invention is the provision of simple means for quickly smothering a fire in the hold of a vessel without the use of damaging water or liquid.

A still further object of the invention is the provision of means for providing exhaust or plenum type of ventilation as desired, and for supplying heat-conditioned air where the plenum type is used, all of which is accomplished without the use of fans or blowers.

Other objects and advantages will appear in the description and drawings.

In the drawings:

Fig. 1 is a horizontal sectional view taken along line 1—1 of Fig. 2 and through one of the air induction devices used in this system.

Fig. 2 is a fragmentary sectional view of one of the air induction devices as seen at right angles to the view of Fig. 1.

Fig. 3 is a semi-diagrammatic view of a ship's 55 steam, air, gas, or the like.

2

ventilating system in accordance with one form of applicant's invention.

Fig. 4 is a plan view of the ship of Fig. 3.

Fig. 5 is an enlarged fragmentary semi-diagrammatic view of part of a ship's ventilating system illustrating a slightly different system of control than shown in Fig. 3.

Fig. 6 is an enlarged part sectional and part elevational fragmentary view of a ship's ventilating system as employed for any one of the compartments or rooms in the hold of the ship, and which view illustrates a different form of the invention from that shown in Figs. 3 to 5.

The system shown in Fig. 3 comprises the 15 conventional above-deck ventilators 1, each having a pipe 2 leading therefrom into the various compartments 3 in the hold of the ship, which compartments may be rooms 3 or cargo spaces 4 separated by bulkheads 5. The ventilators have 20 the customary laterally directed bell mouth intake apertures and are swivelly supported at their lower ends 6 (Fig. 5) relative to the respective pipes 2 for rotation about a vertical axis so that the intake mouth may face the wind or be directed away from the wind. Generally at least 25 two ventilators are provided for cargo rooms or compartments where the portholes are few or none, thus a forced, but natural, ventilation may be provided by proper adjustment of the ventilators relative to the wind. All this structure is old.

Heretofore the pipes 2 have merely opened into the rooms 3 or cargo receiving spaces 4. If there were plenty of portholes or doors, the air flowing 35 into said rooms or spaces could be allowed to escape naturally, or by adjusting the ventilators at least one of the pair or more that communicates with each room or space may be adjusted to face the wind for causing air to be forced into

40 the same, while one or more of the others may face away from the wind for drawing air from such room or space.

One of the features of my invention is the provision of an air induction nozzle 10 on the 45 lower end of one or more of the pipes 2 that extend into each room or compartment.

These nozzles 10 are best seen in Figs. 1, 2 in which there is a tube 10' that virtually forms a downward extension of each pipe 2, the sides of 50 which tube converge slightly in downward extension to a throat 11.

An annular chamber 12 having an inner wall 14 is for fluid under pressure and is provided with an inlet 13 for such fluid, which fluid may be

The chamber 12 has an inner wall 14 that extends into the throat 11 and spaced from said throat from say about .005 to about .008 inch providing an annular aperture at 15, the opposite sides of which are substantially parallel to the central axis of the tube 10' and throat 11 so that steam or air ejected from said chamber 12 into said tube 10' will be directed substantially parallel with the axis of said tube. This structure is quite important, particularly where the pipe 2 is fairly long. If the flow of air or steam from aperture 15 were toward the axis of the tube, there would immediately be a turbulence in the tube that would build up a pressure sufficient to render the flow through pipe 2 ineffective for accomplishing the desired result.

The tube 10' and the inner wall 14 of the air chamber 12 extend divergently away from throat 11, thus forming a Venturi-shaped passageway, and said throat 11 is almost the same diameter as pipe 12, no obstruction to the flow of air down pipe 2 from the ventilator 1 is created. Thus the ventilators will function in practically the same manner as though the air induction nozzles were not there when said nozzles are inoperative.

At the present time when many cargo ships come into port a thorough fumigation with a cyanide gas or other effective fumigant is required. Generally several days are required to effectively fumigate a ship's hold, much of which time is consumed in the use of suction blowers, fans, etc. in trying to get rid of the gas so as to be able to load the ship.

In the present instance, the air chambers 12 of the air induction nozzles are connected by steam lines 20 with the ship's boiler 21 or with any desired source of steam. Electric solenoid valves 22 for each of the devices is in the steam line adjacent each nozzle, which valves may be controlled from a remote control box 23 above deck. Upon actuating the valves for opening the steam lines to the air induction nozzles the gas in the compartments below deck is quickly sucked out, and in a matter of from one to several hours, the entire hold is absolutely free of gas and ready to be loaded. The valves 22 are then closed and loading can commence.

In Fig. 5 the same structure is shown as in Fig. 3 in so far as the ventilators 1, pipes 2 and nozzles 10 are concerned. However, in this view, the valve 22 of each of the nozzles 10 is separately controlled by individual switches 25 in switch box 26. Any suitable source of electric power (not shown) such as batteries, etc. may be used for the electrical circuits in which the electric solenoid valves are connected.

In the arrangement shown in Fig. 5, one or all of the air induction nozzles in each compartment may be actuated. Where the compartment has been fairly well exhausted of gas, fresh air may readily be drawn into the compartment by merely operating only one of the several nozzles or the actuation of the several nozzles may be varied as to absolutely insure exhaustion of gas from all parts of the compartment.

In Fig. 6 the ventilators 1 are the same as in the other views. However, instead of the pipe 2 that is connected with one of the ventilators to each compartment, a second air induction nozzle 30 is introduced into said pipe adjacent the swivel base of the ventilator or between the nozzle 10 at the lower end of the pipe 31 and the ventilator 1. This nozzle 30 has its annular aperture 32 directed toward the lower nozzle 10, the latter being identical with the nozzles shown in

the other views. An air compressor 38 supplies air under pressure to a tank 33 and which tank supplies air through lines 34 to all of the air induction nozzles 10 and 30. Solenoid valves 22 in an electrical circuit that includes switches 35 in switch box 36 are adapted to be actuated individually by an operator at said box, the latter being preferably above deck or out of the hold.

The other ventilator or ventilators for each compartment may be identical with those of the preceding figures.

Between the tank 33 and pipe lines 34 may be an air conditioner for either cooling or heating the air in said lines according to the weather. Steam or refrigeration pipes 37 may supply heat or cold for heating or cooling the air as desired.

For passenger ships or large cargo ships this form of the invention may be preferable to the others in that it not only accomplishes all of the results of the others, but also, fresh tempered or conditioned air may be forcibly injected into the rooms for natural escape therefrom or for positive ejection in the event the nozzle 10 on one or more of the other ventilators is used. Furthermore, in fumigating the compartments the ventilator having the nozzle 30 therein may be used to inject gas into the compartments, and such gas may also be used in the compressor so as to get a highly concentrated gas. It is obvious, of course, that the nozzles 10 may be connected with the steam boiler of the ship instead of with the tank 33, inasmuch as it is generally just as suitable for use in exhausting gas or air from the ship as air, and where the nozzles 30 are not used to supply air to compartments, but for the introduction of gas or a fire retardant (in some cases) steam can be used instead of air.

Ventilation or the supply of fresh air to certain or all compartments and the exhaustion of foul air, is seen from the foregoing to be one of the features of the present invention in addition to merely the removal of poison gas. Sometimes only the engine room is equipped with the system, and in such instances, the ventilation and temperature control is efficiently handled.

In the case of fire in the hold of the vessel, an efficient control is effected by merely closing the hatches and any other outlets and actuating the nozzles 10 for exhausting the air and thus starving the fire by depleting the supply of oxygen necessary to maintain combustion. In some instances, a chemical or CO₂ gas can be injected through nozzles 30, and as such gas is heavier than air, it will quickly replace the air at the flame, said nozzles in practically all instances being closely adjacent the ceilings of the compartments.

Once a fire is out the gas and smoke is readily cleared out by using the nozzles 10.

It is pertinent to note that by the use of my invention, the spark hazards accompanying the use of blowers is eliminated. Also the objectionable bulk and weight of blowers is eliminated. Pipes and electrical circuits generally extend to convenient parts of the hold where attachment with the nozzles is readily effected. There being no moving parts in the nozzle, as in blowers, the uncertainty of the latter is avoided, and in any event, the air induction nozzles of the type herein described are capable of moving a far larger amount of air or gas per minute at a higher velocity than any other means of similar size and horsepower of which I am aware.

I claim:

A ship's ventilating system that includes above-

deck ventilators provided with laterally directed air intake opening and air pipes extending downwardly from said ventilators respectively into the hold of the ship, an annular fluid actuated air induction nozzle on the lower end of each of said pipes provided with a central throat coaxial with the pipe to which it is secured, said central throat being the discharge outlet for air conducted from said ventilator through said pipe, an annular aperture extending around the throat in each nozzle having sides substantially parallel with the walls of said pipe, and each of said apertures being directed upwardly for discharging fluid into said pipes toward said ventilators for inducing a flow of air or gas in said hold outwardly thereof through said pipes and ventilators when said fluid is passed through said apertures into said pipes, means for conducting fluid under pressure to said apertures for so inducing said flow of air or gas, said hold including a plurality of separate compartments and a pair of said pipes and nozzles being in each of said compartments, means for

selectively admitting said fluid to said nozzles as desired whereby one or more nozzles in each compartment may be actuated exhausting said compartments or for causing a forced circulation of air in said compartments.

EDWARD LAMB.
